WILLIAM H. MILLER AND GEORGE W. MILLER, OF MERIDEN, CONNECTICUT.

Letters Patent No. 103,352, dated May 24, 1870.

IMPROVEMENT IN POCKET CUTLERY.

The Schedule referred to in these Letters Patent and making part of the same

To all whom it may concern:

Be it known that we, WILLIAM H. MILLER and GEORGE W. MILLER, of Meriden, in the county of New Haven and State of Connecticut, have invented a new and useful Improvement in Pocket-Cutlery; and we do hereby declare that the following is a full, clear, and exact description thereof, reference being had to the accompanying drawings making part of this specification, and to the letters of reference marked thereon, in which—

Figure 1 represents a knife having the covering of the handle attached to the scales by screws.

Figure 2 is another view of the same with the covering of one side removed.

Figure 3 is a side view of a knife, showing the scale with cover removed, and the mode of securing the scale, back spring, and blade together.

Our invention relates to the manufacture of pocket-cutlery, and consists in a method of first firmly securing the scale to the back spring and to the blade of a pocket-knife, so that the strain in using the knife shall all be exerted upon those rivets, or that part of the rivets which secure the scales to the back spring and to the blade; and the covering of wood, pearl, hard rubber, or any other desirable material, and the said covering may then be attached to the scales by small screws *i* passing through the covering *a* into the threaded holes *i*.

c c represent the scales, which are secured to the back spring *l* by means of the rivets *n*, which are headed down flush with the outside of the scales *c*.

The blade *b* is secured in place by the rivet *e*, which is also headed down upon the scales *c*, so that, when the rivets are all headed down, the outside of the scales shall present a generally flat surface.

Holes *i*, having a screw-thread cut therein, are then made in the scales *c*, and corresponding holes are made in the covering *a*, which may be of wood, pearl, hard rubber, or any other desirable material, and the said covering may then be attached to the scales by small screws *i* passing through the covering *a* into the threaded holes *i*.

It will be seen that in this device the working parts of the knife are fully operative without the covering *a*, which is attached for the sake of appearance, and to give a smooth and desirable form.

When attached in this way, the covering will not split or crack at the points where it is riveted to the scales, as there is no strain at those points, while all the rivets which secure the scales, back spring, and blade together, being headed firmly down against the scales *c*, the knife is made much stronger and stiffer than when made in the usual manner.

When made according to our improved method, as herein described, there is no necessity of any bolster at the end of the handle to which to head the rivet securing the blade, and, as there is no necessity of finishing down the head of that rivet, it is not so liable to give way or become loose, as the head of the rivet under the covering *a* may be as large and strong as desirable, without injuring the appearance of the knife in the least.

We are aware that the covering to the scales of pocket-cutlery has been secured to the same by turning the edge of the scales over the edge of the covering, as shown in Letters Patent granted to C. H. Palmer, April 30, 1867, and we do not claim the same, nor any part thereof; but, having thus described our invention,

What we claim as new, and desire to secure by Letters Patent, is—

An improvement in pocket-cutlery, wherein the blade *b* and back spring *l* are first secured or riveted to the scales *c c*, and the covering *a* afterward secured to the scales *c* by means of small screws or rivets, substantially as herein described.

WM. H. MILLER.
GEO. W. MILLER.

Witnesses:

ORVILLE H. PLATT,
JOHN Q. THAYER.

That others skilled in the art may be able to make and use our invention, we will proceed to describe its construction and application to use.

In the drawings—
